Primary Examiner—Ted Shooman*Assistant Examiner*—C. Tuttle*Attorney, Agent, or Firm*—Ernestine C. Bartlett**[57] CLAIM**

The ornamental design for a steam hair curling set, as shown and described.

DESCRIPTION

FIG. 1 is a front, top, right side, perspective view showing my new design with the cover element removed for completeness of disclosure;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a perspective view showing my new design with the protective cover in place;

FIG. 8 is a perspective view showing my new design with the parts separated;

FIG. 9 is a front elevational view of the cover element, shown separated from the base for clarity;

FIG. 10 is a rear elevational view thereof;

FIG. 11 is right side elevational view thereof;

FIG. 12 is a left side elevational view thereof;

FIG. 13 is a top plan view thereof; and,

FIG. 14 is a bottom plan view thereof.
